ENGINE CONTROL SYSTEM

Eric C. Wahlberg, Stamford, Conn., assignor to
 Electrolux Corporation, Old Greenwich, Conn.,
 a corporation of Delaware

Application October 30, 1943, Serial No. 508,425

17 Claims. (Cl. 172—293)

The present application is a continuation-in-part of my copending application, Serial No. 501,405 filed September 6, 1943, and relates back thereto for all common subject matter.

In my copending application there is disclosed a control system whereby the speeds of a plurality of prime movers, such as the internal combustion engines on a multi-engine aircraft, may be varied in substantial synchronism. As shown in said application, the speed of each engine is controlled by an individual governor, and the settings of all the governors may be varied in synchronism in order to accomplish substantially synchronous changes in speeds of the engines.

In a multiengine aircraft it is also desirable to have it possible to vary the speeds of the various engines independently, usually under the control of an officer other than the pilot, such as the flight engineer, for the purpose of testing the several engines. However, it is also desirable that the pilot be able to take the control away from the flight engineer instantaneously at any time and to re-synchronize the engines.

In accordance with the present invention, a separate switch is provided by means of which the settings of the several governors may be varied independently of each other to thereby individually adjust the speeds of the engines controlled by the respective governors. However, the pilot is always able to re-synchronize the engines by simply manipulating the same control member as is employed to change their synchronous speeds.

Further objects and advantages of my invention will be apparent from the following description considered in connection with the accompanying drawings, which form a part of this specification, and of which:

Fig. 1 is a straight-line style of wiring diagram illustrating a preferred embodiment of my invention;

Fig. 1a is an explanatory key for the relays embodied in Fig. 1. In the key the contacts of each relay are shown in vertical alignment with each other and with the solenoid or heating element which actuates them, contacts located above the broken line being those employed in the control circuits shown in the left portion of Fig. 1, while the contacts located below this line are those employed in the motor circuits shown in the right portion of Fig. 1; and

Fig. 2 is a schematic wiring diagram of one of the motors shown in Fig. 1.

In Fig. 1, numerous magnetic and thermorelays are schematically shown. The solenoids of the

magnetic relays are shown as coils, while heating elements of the thermorelays are shown as a series of straight lines joined at angles of 90°. The solenoids and heating elements are designated by capital letters and the various contacts forming parts of the different relays are designated by the same capital letter which designates the solenoid or heating coil of that relay with a number added thereto. Thus, the contacts actuated by the solenoid A are designated A₁ and A₂. Contacts which are normally open, that is when the coil of the relay is not energized, are shown as two spaced rectangles, such as contact A₂, while contacts which are normally closed are shown by two contiguous rectangles, such as contact A₁.

Reference character 10 designates a conductor for supplying suitable current for energizing the various relay coils. The heating coil B of a thermorelay is connected in series with the normally closed contact A₁ and the normally open contact C₂ between the conductor 10 and ground. The solenoid C of a magnetic relay is connected to the conductor 10 through the normally closed contact B₁ and to ground through the normally open contacts A₂ and C₁ connected in parallel.

The solenoid D is connected to the conductor 10 through a limit switch 12, the function and operation of which will be explained hereinafter. The other side of the solenoid D is connected to the pole 14 of a double throw switch 16, and through a normally open contact P₁ to ground.

The solenoid E is connected through a limit switch 18 to the conductor 10 and the other side of the solenoid is connected to the pole 20 of the switch 16, and through the normally open contact Q₁ to ground. The solenoid F is connected to the conductor 10 through a limit switch 22 and the other side is connected to the pole 24 of a double throw switch 26, and through the normally open contact P₂ to ground. The solenoid G is connected through a limit switch 28 to conductor 10 and the other side is connected to the pole 30 of switch 26, and through the normally open contact Q₂ to ground.

The blades of switches 16 and 26 are connected together by means of a conductor 32, which is connected through normally closed contact Y₁ and the solenoid A to ground. The solenoid A may be connected to the line 10 through the normally open contact Y₂ connected in series with a resistor 11 having the same resistance as the solenoids D, E, F or G.

The solenoid K is connected directly to the line 55 and to ground through a normally open limit

switch 12' and a pair of parallel connected signal bulbs 46 and 48, and through a normally open limit switch 22' and a pair of signal lamps 50 and 52. Solenoid L is connected directly to conductor 10 and through normally open limit switches 18' and 28' and signal lamps 46 and 48, and 50 and 52, respectively, to ground.

Reference character 54 designates a switch which is generally similar to the switch disclosed in my aforesaid copending application. This switch includes a rotatably mounted disc 56 on which is mounted contact segments 58 and 60. This disc may be rotated by means of a pinion 62 driven by an electric motor to be subsequently described. A manually turnable contact arm 64 is mounted concentrically with respect to disc 56, but independently thereof so that turning of the arm does not rotate the disc and rotation of the disc does not turn the arm. Switch 54 also includes normally open limit switches 66 and 68 which are so arranged as to be closed when the arm 64 is turned to its extreme right or left positions, respectively.

The solenoid M is connected to the conductor 10 through the normally closed contact L₁ and to the contact segment 58 of switch 54 through the normally closed contact Y₃. The solenoid N is connected to the conductor 10 through the normally closed contact K₁, and to the segment 60 through the normally closed contact Y₅. The solenoids P and Q are connected to the conductor 10 through the normally closed contacts M₁ and N₁ in series. The solenoid P is connected to the contact segment 60 through the normally open contact Y₆, and to ground through the normally open contact P₅ and resistor 69, while the solenoid Q is connected to the contact segment 58 through the normally open contact Y₄, and to ground through the normally open contact Q₅ and the resistor 69.

A conductor 70 is connected to conductor 10 through the normally open contacts R₁ and T₁ in parallel, while the solenoid R is connected to the conductor 70 through the normally open contacts M₂ and N₂ in parallel.

A conductor 72 is connected to the conductor 10 through the normally open contacts M₃, N₃ and U₁ in parallel. The heating element T of a thermo relay is connected through the normally closed contact R₂ to the conductor 72, the other side of the coil being grounded. The solenoid U is connected to the conductor 72 through the normally closed contacts W₁ and Y₇, the other side of the solenoid being grounded.

The heating coil W of a thermo relay is connected between the conductor 10 and ground and in series with the normally closed contacts M₄ and N₄ and the normally open contact U₂.

The solenoid Z is connected in series with the normally closed contacts P₄ and Q₄ between the arm 64 and ground. A signal lamp 74 is shunted around solenoid Z and the contacts P₄ and Q₄. Shunted in a similar manner are the solenoids H and J connected in series with normally open contacts P₃ and Q₃, respectively. The resistance of resistor 69 is equal to the resistance offered by the parallel circuit comprising the signal lamp 74 and the solenoids Z, H or J. One of the contacts of each of the limit switches 66 and 68 are connected directly to the line 10. The other contacts of these limit switches are connected together and through the solenoid Y to ground. In other words, the switches 66 and 68 are connected in parallel between the line 10 and the solenoid Y.

Reference character 60 designates a conductor for supplying suitable current for operating the

electric motors. A conductor 99 is connected to conductor 88 through normally open contacts C₃ and U₉ in parallel. As shown, there are three motors having commutators 82, 84 and 86, pairs 5 of slip rings 83, 89 and 92, respectively, and field windings 84, 96 and 98 respectively.

The field windings are connected in parallel, one side being grounded while the other side is connected to the conductor 99.

10 The slip rings 88 are connected between conductor 100 and 102 through normally open contacts U₃ and U₄. Slip rings 89 are connected between the conductors through normally open contacts U₅ and U₆, while slip rings 92 are connected between conductors 100 and 102 through normally open contacts U₇ and U₈. Conductor 100 is connected to ground through normally closed contact R₄ and normally open contact U₁₀ in series. Conductor 102 is connected to the conductor 99 through the normally closed contacts R₃.

15 A conductor 104 is connected to the conductor 99 through the normally open contacts M₅ and R₅ in series, and to ground through the normally open contacts N₆, R₆ and U₁₀ in series. A conductor 106 is connected to conductor 99 through normally open contacts N₅ and R₆ in series, and to ground through normally open contacts M₆, R₆ and U₁₀ in series.

20 Commutator 82 is connected between conductors 104 and 106 through normally open contacts Z₁ and Z₄. Commutator 84 is connected between these conductors through normally open contacts Z₅ and Z₈, while commutator 86 is connected between conductors 104 and 106 through normally open contacts Z₉ and Z₁₂.

25 A conductor 108 is connected directly to ground and a conductor 110 is connected directly to the line 88. The upper brush of armature 82 may be connected to the ground wire 108 through normally closed contact Z₂ and normally open contact H₂, or to conductor 110 through normally closed contact Z₂ and normally open contact J₂. The other brush of commutator 82 may be connected to the conductor 110 through normally open contact Z₃ and normally open contact H₂, or to the ground wire 108 through normally closed contact Z₃ and normally open contact J₃. The brushes of this commutator may be connected together to short circuit the armature of the motor through normally closed contacts Z₂, H₁, J₁ and Z₃. Similar connections are provided for commutators 84 and 86, whereby these commutators may be connected across conductors 108 and 110 and the polarity of the armatures with respect to these conductors may be reversed.

30 As shown, the motor having commutator 82 drives the pinion 62 which as above described, is arranged to rotate the disc 56 of switch 54. The remaining motors may be connected, as is shown for one motor in Fig. 2, to drive a pinion 112 which engages a rack 114 arranged to vary the tension on the speeder spring 116 of a governor. As is well known, the governor is driven by a prime mover, such as an internal combustion engine, and is arranged to maintain the speed of the engine constant in any preferred manner. As disclosed in my above mentioned copending application, the governor controls the pitch of a propeller driven by the internal combustion engine.

35 Also illustrated in Fig. 2 is the arrangement of the limit switches 12, 12', 18 and 18', which are associated with the motor there shown. Rack 114 is provided with arms 118 and 120, arranged 40 to actuate the limit switches when the rack is at

the limits of its travel. Thus, when the rack is moved to the left as viewed in the figure, so as to increase to a maximum the tension of spring 116, the arm 112 will open limit switch 12, and close limit switch 12'. On the other hand, when the rack has been moved to the right so as to decrease to a minimum the tension on the spring 116, the arm 120 will open limit switch 18 and close limit switch 18'. Increasing the tension of the speeder spring increases the speed of the engine, and vice versa, as is well known.

Fig. 2 also shows the manner in which the slip rings are connected to fixed taps on the armature winding of the motor. As is fully explained in my copending applications, Serial No. 428,018 filed January 24, 1942, and Serial No. 472,464 filed January 15, 1943, when current is applied to the armature winding through the slip rings, the field being excited, the armature will line up in a predetermined position with respect to the field. Moreover, if a plurality of these motors have their respective slip rings connected in parallel, they run in synchronism with each other when current is applied to the armature through the brushes.

The above described device operates as follows:

It will first be assumed that the governor settings, as determined by the tension of the speeder springs, is the same and consequently the governors maintain the internal combustion engines in synchronism with each other at a speed determined by the governor settings. Should the pilot wish to change the speed of the several engines, he moves the contact arm 64 in one direction or the other, depending upon whether he wishes to increase or decrease the engine speed, and it is assumed that movement in a clockwise direction into contact with segment 60 results in an increase in speed. Contact between arm 64 and segment 60 establishes a circuit from ground through normally closed contacts P₄, Q₄, solenoid Z, normally closed contact Y₅, solenoid N and normally closed contact K₁ to the line 10, thus energizing solenoids N and Z and lighting the signal lamp 74 which is in parallel with solenoid Z. Consequently, contacts N₁ and N₄ are opened, while contacts N₂, N₃, N₅ and N₆ are closed, and contacts Z₂, Z₃, Z₆, Z₇, Z₁₀ and Z₁₂ are opened, while contacts Z₁, Z₄, Z₅, Z₈, Z₉ and Z₁₁ are closed.

Closing of N₂ does not immediately energize solenoid R because contacts R₁ and T₁ are both open. However, closing of contact N₃ does immediately energize solenoid U through the normally closed contacts W₁ and Y₇ with the result that all of the U contacts are closed. Closing of U₉ supplies current from the line 80 to the field windings 94, 96 and 98 and also to the conductor 102 through the normally closed contact R₃. Closing of U₁₀ connects the conductor 103 to ground through the normally closed contact R₄. Inasmuch as contacts U₃ to U₈ have been closed, the slip rings 88, 90 and 92 are connected across the conductors 103 and 102 and hence current is supplied through the slip rings to position the several armatures with respect to their fields, as explained above in connection with Fig. 2. During this positioning period current is not supplied to the armatures through their commutators, because contacts R₅ and R₆ are still open, although contacts N₅ and N₆ have been closed.

Closing of N₃ also supplies current to the heating coil T. A certain length of time is required for the heating of this coil, which time is sufficient for the above described positioning of the armatures to take place. Thereupon, contact T₁

is closed, thus completing the circuit from the line through closed contact N₂ to solenoid R. Energization of this solenoid closes contact R₁ to provide a holding circuit for solenoid R, and opens contact R₂ to drop out heating element T. Cooling of this element opens contact T₁, but solenoid R remains energized because R₁ has been closed. Contacts R₃ and R₄ are opened, thus disconnecting the slip rings from the line. However, the slip rings remain connected together in parallel due to the fact that contacts U₃ through U₈ are closed. Contacts R₅ and R₆ are closed by the energization of solenoid R and consequently conductor 104 is connected to ground and conductor 106 is connected to the line 80. The closing of contacts Z₁, Z₄, Z₅, Z₈, Z₉ and Z₁₂ connects the upper brush of each commutator to ground through the conductor 104, and connects the lower brush to the line 80 through conductor 106. The opening of contacts Z₂, Z₃, Z₆, Z₇, Z₁₀ and Z₁₁ removes a short circuit of each of the commutators, and the motors operate in the proper direction to increase the tension on the speeder springs of the governors, and to drive the disc 58 in a clockwise direction. Due to the fact that the slip rings are connected in parallel, all of the motors operate in synchronism and hence the settings of the governors are changed by equal amounts.

Disc 56 is rotated until the insulated space between the segments 58 and 60 is turned into alignment with the arm 64, which was turned by the pilot a certain distance in a clockwise direction. The further the arm 64 was turned, the greater the angle through which the disc 58 must be rotated by the motor and consequently the greater the change in governor setting effected by the other motors. Therefore, the angle through which the arm is turned is a measure of the speed change and a suitably calibrated scale may be provided in order to show the position to which the arm 64 should be turned for any desired speed of the engines.

When contact between arm 64 and segment 60 is broken by the above described rotation of disc 56, solenoids Z and N are de-energized and hence contacts N₅, N₆, Z₁, Z₄, Z₅, Z₈, Z₉ and Z₁₂ are opened, thus interrupting the supply of current to the several commutators. At the same time, contacts Z₂, Z₃, Z₆, Z₇, Z₁₀ and Z₁₁ are closed and consequently the several armatures are short circuited through these contacts and normally closed contacts H₁, J₁, F₁, G₁, D₁ and E₁. This provides dynamic braking circuits which very rapidly decelerate the motors so as to prevent any tendency to coast.

De-energization of solenoid N also opens contact N₂, thus de-energizing solenoid R, which closes contacts R₃ and R₄ and opens contacts R₅ and R₆. Opening of contact N₃ does not de-energize solenoid U, inasmuch as contact U₁ is closed and consequently conductor 102 is connected to the line 80 through contacts U₉ and R₃, while conductor 103 is grounded through contacts U₁₀ and R₄. Contacts U₂ to U₈ being closed, current is supplied to the slip rings so as to position the armatures of the several motors in exactly the same positions with respect to their fields after they have been stopped by the dynamic braking. The closing of contact N₄ by the de-energization of solenoid N supplies current to heating coil W which, after a time delay sufficient to permit the above-described positioning of the armatures, opens contact W₁ to thereby de-energize solenoid U. Consequently, all of the U con-

tacts are opened and the supply of current to the fields, slip rings and heating coil W is interrupted.

If the pilot wishes to decrease the speeds of the motors, he turns the arm 64 in a counter-clockwise direction into contact with segment 52 to thus energize solenoids Z and M. Inasmuch as the contacts M₂ and N₂ are connected in parallel and contacts M₃ and N₃ are also connected in parallel, current will be supplied to the field windings and to the slip rings in order to position the armature in exactly the same manner as above described when the arm 64 was turned clockwise to energize relay N. However, contacts M₅ and M₆ are closed so as to connect the conductor 104 to the line 80 and conductor 106 to ground, whereas, when relay N was energized, conductor 104 was connected to ground and conductor 106 was connected to the line. The effect of this is to reverse the polarity of the armatures of the several motors with respect to their fields, and consequently the motors run in the opposite direction, so as to reduce the tension on the speeder springs and to drive the disc 56 in a counterclockwise direction. When the contact between the arm 64 and the segment 58 is broken, the motors are dynamically braked and angularly positioned with respect to their fields in the same manner as above described.

Should the flight engineer, who normally has control of the switches 16 and 26, wish to change the speed of one of the engines with respect to the speed of the other, he may do so by means of these switches. Closing the contact 14 of switch 16 causes the motor having the armature 86 to rotate in the direction which changes the setting of the associated governor so as to increase the tension of the governor speeder spring, which in turn increases the speed of the associated engine, while closing the contact 20 decreases the speed of the engine. Likewise, closing contact 24 of switch 26 increases the speed of the other engine, while closing contact 30 decreases the speed of this engine.

When contact 14 is closed, a circuit is established from the line 10 through the limit switch 12, solenoid D, switch 16, normally closed contact Y₁ and solenoid A to ground. Should, however, the governor already be at the extreme position towards which the closing of contact 14 would drive it, limit switch 12 will be open and the circuit will not be completed. Assuming however, the switch 12 is closed, energization of solenoid A opens contact A₁ and closes contact A₂, thus energizing solenoid C through normally closed contact B₁. Energization of solenoid C closes contact C₃, thus connecting conductor 99 to the line 80 to thereby supply excitation current to the field windings of the various motors. Energization of solenoid D closes contacts D₂ and D₃ and opens contact D₁. Closing of D₂ connects the lower brush of armature 86 to conductor 109 and hence to line 89, inasmuch as contact Z₁₁ is closed, while closing of D₃ connects the upper brush of this commutator through normally closed contact Z₁₀ to the ground wire 108. Consequently, the armature 86 is rotated, but the other armatures do not rotate because none of the solenoids F, G, H, or J is energized. Due to the fact that the solenoid U has not been energized, the contacts U₃ to U₄ are all open and hence the slip rings of the various motors are not connected in parallel. Therefore, the motor having the armature 86 may operate independently of the others. This motor continues to operate until either the flight engineer opens the contact

14 or the rack 114 driven by this motor reaches its extreme position to thereby open the limit switch 12, in either of which events the solenoids A and D are de-energized. Solenoid C, however, 5 remains energized due to the fact that contact C₁ is closed and therefore field current is supplied through the contact C₃. De-energization of solenoid D opens contacts D₂ and D₃ to interrupt the supply of current to armature 86, and closes contact D₁ to provide a short circuit of the armature which, inasmuch as the field remains excited, dynamically brakes this motor. De-energization of solenoid A closes contact A₁, and inasmuch as contact C₂ is closed, current is supplied to the heating coil B. After a delay sufficient for the dynamic braking to take place, the coil B is heated sufficiently to open contact B₁, thus de-energizing solenoid C. This, in turn, opens contact C₂ to drop out heating coil B, and 10 opens contact C₃ to interrupt the supply of field current. When coil B cools and contact B₁ closes, solenoid C is not again energized because both contacts A₂ and C₁ are now open.

If the rack 114 has been driven to its extreme 25 position, limit switch 12' is closed to thus complete a circuit through solenoid K and the signal lamps 48 and 48'. One of these lamps is located in the flight engineer's compartment, while the other is located in the pilot's compartment, and 30 the lighting thereof notifies both of these officers that the governor is at one or the other of its extreme positions.

Energization of solenoid K by the closing of limit switch 12' opens contact K₁ to thus make 35 impossible the energization of solenoid N if the pilot should turn the arm 64 into contact with segment 60. If the governor driven by the armature 86 is already at its extreme position for maximum engine speed, it obviously cannot be driven any further in this direction and if the pilot attempts to drive it further, he is prevented from doing so due to the fact that contact K₁ is open. However, the pilot may cause all of the motors to 40 run in the opposite direction by turning arm 64 into contact with segment 58 to thus energize solenoids Z and M. In the manner previously described, this first positions all of the armatures with respect to their fields and then causes the motors to run in synchronism in the proper direction to decrease the governor settings. The 45 settings of the several governors are hence changed by like amounts and therefore the speeds of the different engines are varied by equal amounts. However, due to the fact that switch 16 was closed so as to change the speed of one engine with respect to that of the other, the two engines are not in synchronism at the time arm 64 is moved into contact with segment 58, and 50 completion of this circuit does not re-synchronize the engines, but as above stated, changes their speeds by equal amounts. Thus, to take a concrete example, assuming that the engines, as controlled by the governors, have a range from 900 to 2700 R. P. M., it will be further assumed that they 55 were running in synchronism at 2500 R. P. M., before switch 16 was closed. If this switch is closed to complete the circuit through contact 14 and left closed, one of the governors will be run to its maximum limit and will open limit switch 12, and close switch 12' with the result that the speed of the engine controlled thereby will be increased to its maximum of 2700 R. P. M., while the other engine continues to run at 2500 R. P. M. 60 65 70 75 Under these conditions, if the pilot turns arm

64 into contact with segment 60, nothing happens because contact K₁ has been opened through the energization of relay K resulting from the closing of limit switch 12'. However, if the pilot turns the arm 64 into contact with segment 58 through the proper angle to reduce the speed of the one engine, for example from 2500 to 2200 R. P. M., the speed of the other engine will be reduced an equal amount, namely from 2700 to 2400 R. P. M.

If, instead of increasing the speed of one engine, the flight engineer wishes to decrease its speed, he throws switch 16 from its neutral or "off" position so as to complete the circuit through contact 20. Consequently, solenoids A, C and E are energized in the same manner as solenoids A, C and D were energized when the switch 16 was closed in the opposite position. Contact C₃ is thus closed to excite the fields 94, 96 and 98 and contact E₁ is opened and contacts E₂ and E₃ are closed. Consequently, the lower brush of armature 86 is connected through Z₁₁ and E₃ to the ground wire 108 and the upper brush is connected through Z₁₀ and E₂ and wire 110 to the line 80. Thus, the polarity of armature 86 has been reversed with respect to what it was when solenoid D was energized to close contacts D₂ and D₃, and hence the armature rotates in the opposite direction so as to decrease the governor setting, which in turn reduces the speed of the engine controlled thereby.

In a similar manner, the flight engineer may vary the speed of the other engine by manipulating the switch 26. Closing this switch through contact 24 energizes solenoids A, C and F to close contact C₃ to excite the field windings and to close contacts F₂ and F₃ to thereby connect the lower brush of armature 84 through contacts Z₇, F₂ and wire 110 to line 80 and to connect the upper brush through contacts Z₆ and F₃ to the ground wire 108. Contact F₁ is opened to open the dynamic braking short circuit and consequently armature 84 rotates in the proper direction to increase the setting of the governor associated therewith and hence to increase the speed of the engine controlled by this governor. The speed of this engine may be decreased by closing the switch 26 through contact 30 to thereby energize solenoids A, C and G. This opens contact G₁ and closes contacts G₂ and G₃ to thereby connect the lower brush of armature 84 to the ground wire 108 and to connect the upper brush to the line 80. Under these conditions, the polarity of the armature having been reversed, the motor will run in the opposite direction so as to decrease the governor setting. If the switch 26 is left closed through contact 24, the governor will be driven to its extreme maximum range, whereupon limit switch 22 is opened and switch 22' is closed. Opening of switch 22 de-energizes solenoid F in the same manner that opening of limit switch 12 de-energized solenoid D, while closing of limit switch 22' energizes solenoid K and lights the signal lamps 50 and 52. If the switch 26 is left closed through contact 30, limit switch 28 will be opened and switch 28' closed when the governor is driven to its minimum limit. Opening of switch 28 de-energizes solenoid G so as to stop the armature 84, while the closing of limit switch 28' lights the signal lamps 50 and 52 and energizes the solenoid L. As above described, energizing of solenoids K or L opens the contacts K₁ or L₁, respectively, so as to prevent the energization of solenoids N or M, respectively, in the event that the pilot should turn the contact arm 64 in a direction which would

tend to run the motor having the armature 84 past its limit position.

If the pilot wishes to re-synchronize the engines he may do so at any time by turning the arm 64 all the way to the right so as to close the switch 66, or all the way to the left so as to close the switch 68. Turning the arm to the right will synchronize the engines at their minimum speed, while turning it to the left will synchronize them at their maximum speed. Thereafter, the pilot may change the synchronous speeds of the engines to any value desired by turning the arm 64 through the proper angle in the manner first described above.

Assuming that the pilot wishes to re-synchronize the engines at the maximum speed, turning of the arm 64 to the left in order to close switch 68 first completes the circuit through the arm and the segment 60 so as to energize solenoids Z and N. This closes contacts N₂ and N₃. The closing of the latter contact energizes solenoid U through normally closed contacts W₁ and Y₇ and supplies current to the heating coil T through the normally closed contact R₂. Energization of solenoid U closes all the U contacts and consequently excites the fields and supplies current to the slip rings 88, 90 and 92 of the various motors so as to tend to position their armatures with respect to their fields. However, before heating coil T has time to heat sufficiently to close contact T₁ so as to energize solenoid R, which would result in the motors running in synchronism, the arm 64 closes switch 68 so as to energize solenoid Y. This opens contacts Y₁, Y₃, Y₅ and Y₇ and closes contacts Y₄ and Y₆. Opening of contact Y₅ de-energizes solenoid N to thus close contact N₁ and to open contacts N₂ and N₃. Closing of contact N₁ energizes solenoid P inasmuch as this solenoid is connected through contact Y₆, segment 60, arm 64 and signal lamp 74 to ground. Although contact Y₄ is closed, solenoid Q is not energized because arm 64 is not in contact with segment 58 and hence no circuit is completed through the solenoid. Opening of contact Y₇ immediately de-energizes solenoid U, thus opening all of the U contacts and disconnecting the slip rings from the wires 100 and 102 and hence from each other.

In the event either or both of the switches 16 and 26 are closed at the instant that the pilot closes the switch 63 to re-synchronize the engines, the opening of contact Y₁ interrupts the circuit or circuits thus completed through any of the solenoids D, E, F or G. At the same time, the closing of contact Y₂ connects the solenoid A to the line 10 through the resistor 11. Inasmuch as this resistor has the same resistance as the solenoids D, E, F or G, the same voltage is applied to the solenoid A as is applied when solenoid A is connected to the line 10 in series with any of the solenoids D, E, F or G. Energization of the solenoid A closes contact A₂ to thus energize solenoid C which results in the closing of contact C₃ so as to supply excitation current to the field windings.

Energization of solenoid P closes contacts P₁, P₂ and P₃ so as to energize solenoids D, F and H, respectively, and closes contact P₅ to provide a holding circuit for solenoid P through resistor 69 to ground. Normally closed contact P₄ is opened so as to de-energize solenoid Z, thus opening contacts Z₁, Z₄, Z₅, Z₈, Z₉, and Z₁₂ and closing contacts Z₂, Z₃, Z₆, Z₇, Z₁₀ and Z₁₁. Energization of solenoids D, F, and H opens contacts D₁, F₁ and H₁, so as to open the dynamic short circuit

of each armature, and closes contacts D₂, D₃, F₂, F₃, H₂, and H₃ so as to connect the lower brush of each armature to conductor 110 and hence to the line 80, and to connect the upper brush of each armature to the ground wire 108. Consequently, the armatures 84 and 86 will rotate in the proper direction to increase the tension on the speeder springs of the respective governors, and the armature 82 will drive the disc 56 in a clockwise direction so as to bring the insulated space between the segments 58 and 60 into alignment with the arm 64. The motors will not operate in synchronism, due to the fact that the contacts U₃ to U₈ are opened, but each motor will run until it actuates its limit switches. Thus, armature 86 will rotate until limit switch 12 is opened to thereby drop out solenoid D, which opens contacts D₂ and D₃ to interrupt the supply of current to the commutator and closes contact D₁ to dynamically brake this motor. This, however, does not interfere with the operation of the other motors and consequently armature 84 will rotate until it opens limit switch 22 to drop out solenoid F, while armature 82 will run until it rotates disc 56 sufficiently to bring the insulated space between segments 58 and 60 into alignment with arm 64. This drops out solenoid H which interrupts the supply of current to, and dynamically brakes armature 82.

Should armature 82 rotate disc 56 to the "off" position before either or both of the other motors have reached their limits, opening of the circuit through arm 64 and segment 60 will not drop out solenoid P because of the holding circuit established through contact P₅ and resistor 69 to ground.

Consequently, the settings of both of the governors have now been re-synchronized at their maximum settings and therefore both of the engines have been synchronized at maximum speed, while the disc 56 has been rotated so as to break the contact between segment 60 and arm 64. Thereafter, the pilot may synchronously decrease the settings of the governors if he wishes the engines to run at something less than their maximum speed, by turning the arm 64 counterclockwise into contact with segment 58. This opens the switch 68, thus de-energizing solenoid Y and opening contact Y₂, so as to de-energize solenoid A. This in turn closes contact A₁, thus supplying current to the heating coil B, with the result that contact B₁ is opened to drop out solenoid C, as has been previously described. Contact Y₆ is also opened to drop out solenoid P.

Should the pilot wish to maintain the engines at their maximum speed, he will not turn the arm 64 counter-clockwise and hence switch 68 remains closed and solenoids Y, P, A and C remain energized. This is not objectionable except that it consumes a small amount of current and the energization of solenoid C keeps contact C₃ closed and the fields excited. However, it will rarely, if ever, occur in practice that the pilot will keep the engines at their maximum speed for any substantial length of time.

The provision of contact Y₂ in series with the switches 16 and 26 is necessary in order to eliminate the possibility of a short circuit in the event the pilot re-synchronizes the engines at the same time that one or both of these switches are closed. If, for instance, contact 20 of switch 16 is closed, solenoid E is energized and contacts E₂ and E₃ closed. Under these conditions, if arm 64 is turned so as to close limit switch 68, it energizes solenoid Y which closes contact Y₆ to ener-

gize solenoid P which closes contacts P₁ and P₂ to energize solenoids D and F. Energization of solenoid D closes contacts D₂ and D₃, and if contacts E₂ and E₃ were still closed, line 80 would be connected directly to the ground wire 108. However, as soon as solenoid Y is energized it opens contact Y₁ to immediately drop out solenoid E, thus opening contacts E₂ and E₃ to prevent such a short circuit.

- 10 If, instead of having turned the arm 64 all the way to the left so as to re-synchronize the engines at their maximum speed, the pilot turns it all the way to the right, so as to re-synchronize them at their minimum speed, this closes the limit switch 66 which energizes the solenoid Y in the same manner as previously described, inasmuch as the switches 66 and 58 are connected in parallel. However, under these conditions the solenoid P is not energized because arm 64 is not in contact with segment 60. On the other hand, solenoid Q is energized through contact Y₄, segment 58, arm 64 and signal lamp 74. This closes contacts Q₁, Q₂, Q₃, and Q₅ to energize solenoids E, G and J and to provide a holding circuit for solenoid Q, and opens contact Q₄ so as to drop out solenoid Z. Energization of solenoids E, G and J opens contacts E₁, G₁ and J₁ to remove the dynamic brake short circuit and closes contacts E₂, E₃, G₂, G₃, J₂ and J₃ so as to connect the lower brush of each commutator to the ground wire 108 and to connect the upper brush to the line. Thus, the polarity of the armatures is reversed and the motors operate in the proper direction to decrease the settings 30 of the governors and to rotate the disc 56 in a counterclockwise direction. The armatures 86 and 84 rotate until they open limit switches 18 and 28 and armature 82 rotates until it has driven disc 56 to the "off" position to thus de-energize 40 the relays E, G and J. In this manner, the engines are re-synchronized at their minimum speed and thereafter the pilot may change the governor settings by turning the arm 64 to the left into contact with segment 60 so as to cause 45 the engines to run in synchronism at any desired speed.

It will thus be seen that I have provided a control system for the engines of a multiengine aircraft by means of which the substantially 50 synchronous speed of the engines are at all times under control of the pilot, who may adjust the speeds to any value within their operational limits by merely a single manual manipulation of a switch. In addition, however, the system permits 55 the speeds of the several engines to be adjusted individually by the manipulation of a separate switch for each engine, which switches may be under the control of an officer other than the pilot, such as the flight engineer, inasmuch as 60 the pilot may at any time substantially re-synchronize the engines independently of any control which has been or is being exercised by the flight engineer.

By the expression "settings of the motors" as 65 used in the claims is meant the number of revolutions the motors are away from their limits. Thus, the settings of the motors are the same, or in other words the settings are in synchronism, if all of the motors must rotate the same 70 number of revolutions in order to actuate their respective limit switches, whereas if the several motors must rotate different numbers of revolutions before they actuate their limit switches, their settings are different. It will be noted too, 75 that the motors may rotate in synchronism even

though their settings are not in synchronism. Thus, if the flight engineer has momentarily closed one of the switches 16 or 26 so as to operate motors 86 or 84, respectively, independently of the other motors to thereby change its setting with respect to the settings of the remaining motors, and thereafter the pilot turns the arm 64 into contact with either segment 58 or 60, but not far enough to actuate either switch 66 or 68, all of the motors will run in synchronism and their respective settings will be changed by equal amounts, but the settings will not be re-synchronized unless the arm 64 is turned far enough to close either switch 66 or 68, whereupon the several motors will be run independently to one or the other of their limits. This changes their respective settings by unequal amounts to thereby bring the settings back into synchronism.

While I have shown and described a system suitable for controlling the governors of two aircraft engines, obviously, any number of governors or other devices may be controlled by adding an electric motor for each additional device and by adding a switch similar to switches 16 and 26 for each additional motor, each additional switch controlling a pair of solenoids connected thereto in the same manner as the pairs D and E, or F and G. Further modifications apparent to a person skilled in the art may be made without departing from the scope of my invention, which is to be limited only by the appended claims.

What I claim is:

1. In a control system, a plurality of similar electric motors, each motor having a field and a wound rotor including a commutator, taps connected to similar fixed points on the rotors of said motors, manually controlled relay means for supplying current to said fields, for connecting said taps in parallel and for supplying current to said taps to position said rotors, a time delay relay actuated by the first-mentioned relay for subsequently interrupting the supply of current to said taps and for supplying current to said commutators to cause said rotors to run in synchronism, and separately manually controlled relay means for supplying current to said fields and said commutators while said taps are disconnected to cause said motors to run individually.

2. In an electric system, a plurality of electric motors, means for starting, running a selected amount between limits and stopping said motors in synchronism to thereby change the settings of the motors by equal amounts, means for operating each motor independently of the other motors a selected amount within said limits to change its setting with respect to that of the other motors, and means for operating all of said motors independently until each motor reaches the same one of said limits to thereby re-synchronize the settings of said motors.

3. In an electric system, a plurality of electric motors, switching mechanism including a manually movable member for starting, running and stopping said motors in synchronism to change the settings of the several motors by equal amounts, separate switches for operating each motor independently to change its setting with respect to that of the other motors, and switching means operable by said member for re-synchronizing the settings of said motors.

4. In an electric system, a plurality of electric motors, switching mechanism including a manually movable member for starting, running a selected amount between limits and stopping said

motors in synchronism to thereby change the settings of the motors by equal amounts, separate switches for operating each motor independently of the other motors a selected amount within said limits to change its setting with respect to that of the other motors, and switching means operable by said member for operating all of said motors independently until each motor reaches the same one of said limits to thereby re-synchronize the settings of said motors.

5. In an electric system, a plurality of electric motors, switching mechanism including a member movable in one direction to cause said motors to start, run in one direction and stop in synchronism and movable in the other direction to cause said motors to start, run in the opposite direction and stop in synchronism to thereby change the settings of the several motors by equal amounts, a separate double throw switch for each motor, means responsive to closure of each switch in one position to run the respective motor independently in one direction and responsive to closure of each switch in the other position to run the respective motor independently in the other direction to change its setting with respect to that of the other motors, and switching means operable by said member for rendering said separate switches inoperative to run said motors and for re-synchronizing the settings of said motors.

6. In an electric system, a plurality of electric motors, switching mechanism including a member movable in one direction to cause said motors to start, run in one direction a selected amount within limits and stop in synchronism and movable in the other direction to cause said motors to start, run in the opposite direction a selected amount within said limits and stop in synchronism to thereby change the settings of the several motors by equal amounts in either direction, a separate double throw switch for each motor, means responsive to closure of each switch in one position to run the respective motor independently in one direction a selected amount within said limits and responsive to closure of each switch in the other position to run the respective motor independently in the opposite direction a selected amount within said limits to change its setting with respect to that of the other motors, and switching means operable by said member for rendering said separate switches inoperative to run said motors and operable for running all of said motors independently in the same direction until each motor reaches the same one of said limits to thereby re-synchronize the settings of said motors.

7. In an electric system, a plurality of electric motors, switching mechanism including a member manually movable in either direction, relay means actuated by movement of said member in one direction to cause said motors to start, run in one direction and stop in synchronism and actuated by movement of said member in the other direction to cause said motors to start, run in the opposite direction and stop in synchronism to thereby change the settings of the several motors by equal amounts in either direction, a separate double throw switch for each motor, relay means actuated by closure of each switch in one position to run the respective motor independently in one direction and actuated by closure of each switch in the opposite position to run the respective motor independently in the opposite direction to change its setting with respect to that of the other motors, and manually controllable relay means for re-synchronizing the settings of said motors.

8. In an electric system, a plurality of electric motors, switching mechanism including a member manually movable in either direction, relay means actuated by movement of said member in one direction to cause said motors to start, run in one direction and stop in synchronism and actuated by movement of said member in the other direction to cause said motors to start, run in the opposite direction and stop in synchronism to thereby change the settings of the several motors by equal amounts in either direction, a separate double throw switch for each motor, relay means actuated by closure of each switch in one position to run the respective motor independently in one direction and actuated by closure of each switch in the opposite position to run the respective motor independently in the opposite direction to change its setting with respect to that of the other motors, and relay means actuated by an extreme movement of said member for re-synchronizing the settings of said motors.

9. In an electric system, a plurality of electric motors, switching mechanism including a member manually movable in either direction, relay means actuated by movement of said member in one direction to cause said motors to start, run in one direction and stop in synchronism and actuated by movement of said member in the other direction to cause said motors to start, run in the opposite direction and stop in synchronism to thereby change the settings of the several motors by equal amounts in either direction, a separate double throw switch for each motor, relay means actuated by closure of each switch in one position to run the respective motor independently in one direction and actuated by closure of each switch in the opposite position to run the respective motor independently in the opposite direction to change its setting with respect to that of the other motors, and relay means actuated by an extreme movement of said member for running said motors independently to re-synchronize the settings of said motors.

10. In an electric system, a plurality of electric motors, switching mechanism including a member manually movable in either direction, relay means actuated by movement of said member in one direction to cause said motors to start, run in one direction and stop in synchronism and actuated by movement of said member in the other direction to cause said motors to start, run in the opposite direction and stop in synchronism to thereby change the settings of the several motors by equal amounts in either direction, a separate double throw switch for each motor, relay means actuated by closure of each switch in one position to run the respective motor independently in one direction and actuated by closure of each switch in the opposite position to run the respective motor independently in the opposite direction to change its setting with respect to that of the other motors, and manually controllable relay means for rendering the second-mentioned relay means inoperative and for re-synchronizing the settings of said motors.

11. In an electric system, a plurality of electric motors, switching mechanism including a member manually movable in either direction, relay means actuated by movement of said member in one direction to cause said motors to start, run in one direction and stop in synchronism and actuated by movement of said member in the other direction to cause said motors to start, run in the opposite direction and stop in synchronism to thereby change the settings of the several motors by

equal amounts in either direction, a separate double throw switch for each motor, relay means actuated by closure of each switch in one position to run the respective motor independently in one direction and actuated by closure of each switch in the opposite position to run the respective motor independently in the opposite direction to change its setting with respect to that of the other motors, and manually controllable relay means for rendering the second-mentioned relay means inoperative and for running said motors independently to re-synchronize the settings of said motors.

12. In an electric system, a plurality of electric
15 motors, switching mechanism including a mem-
ber manually movable in either direction, relay
means actuated by movement of said member in
one direction to cause said motors to start, run in
one direction and stop in synchronism and actu-
20 ated by movement of said member in the other
direction to cause said motors to start, run in the
opposite direction and stop in synchronism to
thereby change the settings of the several motors
by equal amounts in either direction, a separate
25 double throw switch for each motor, relay means
actuated by closure of each switch in one posi-
tion to run the respective motor independently in
one direction and actuated by closure of each
switch in the opposite position to run the respec-
30 tive motor independently in the opposite direc-
tion to change its setting with respect to that of
the other motors, and relay means actuated by
an extreme movement of said member for render-
35 ing the second-mentioned relay means inoper-
ative and for running said motors independently
to re-synchronize the settings of said motors.

13. In an electric system, a plurality of electric motors, switching mechanism including a member manually movable in either direction, relay means actuated by movement of said member in one direction to cause said motors to start, run in one direction a selected amount between limits and stop in synchronism and actuated by movement of said member in the other direction to cause said motors to start, run in the opposite direction a selected amount between said limits and stop in synchronism to thereby change the settings of the several motors by equal amounts in either direction, a separate double throw switch for each motor, relay means actuated by closure of each switch in one position to run the respective motor independently in one direction and actuated by closure of each switch in the opposite position to run the respective motor independently in the opposite direction to change its setting with respect to that of the other motors, and manually controllable relay means for running all of said motors independently until each motor reaches the same one of said limits to thereby re-synchronize the settings of said motors.

60 ~~65~~ 14. In an electric system, a plurality of electric
motors, switching mechanism including a mem-
ber manually movable in either direction, relay
means actuated by movement of said member in
65 one direction to cause said motors to start, run in
one direction a selected amount between limits
and stop in synchronism and actuated by move-
ment of said member in the other direction to
cause said motors to start, run in the opposite
70 direction a selected amount between said limits
and stop in synchronism to thereby change the
settings of the several motors by equal amounts
in either direction, a separate double throw switch
for each motor, relay means actuated by closure
75 of each switch in one position to run the respec-

tive motor independently in one direction and actuated by closure of each switch in the opposite position to run the respective motor independently in the opposite direction to change its setting with respect to that of the other motors, and relay means actuated by an extreme movement of said member for running all of said motors independently until each motor reaches the same one of said limits to thereby re-synchronize the settings of said motors.

15. In an electric system, a plurality of electric motors, switching mechanism including a member manually movable in either direction, relay means actuated by movement of said member in one direction to cause said motors to start, run in one direction a selected amount between limits and stop in synchronism and actuated by movement of said member in the other direction to cause said motors to start, run in the opposite direction a selected amount between said limits and stop in synchronism to thereby change the settings of the several motors by equal amounts in either direction, a separate double throw switch for each motor, relay means actuated by closure of each switch in one position to run the respective motor independently in one direction and actuated by closure of each switch in the opposite position to run the respective motor independently in the opposite direction to change its setting with respect to that of the other motors, and manually controllable relay means for rendering the second-mentioned relay means inoperative and for running all of said motors independently until each motor reaches the same one of said limits to thereby re-synchronize the settings of said motors.

16. In an electric system, a plurality of electric motors, switching mechanism including a member manually movable in either direction, relay means actuated by movement of said member in one direction to cause said motors to start, run in one direction a selected amount between limits and stop in synchronism and actuated by movement of said member in the other direction to cause said motors to start, run in the opposite direction a selected amount between said limits and stop in synchronism to thereby change the settings of the several motors by equal amounts in either direction, a separate double throw switch for each motor, relay means actuated by closure of each switch in one position to run the respective motor independently in one direction and actuated by closure of each switch in the oppo-

site position to run the respective motor independently in the opposite direction to change its setting with respect to that of the other motors, a pair of limit switches associated with each motor, one switch of each pair being arranged to be actuated when the motor associated therewith has been operated to one of said limits and the other switch of said pair being arranged to be actuated when the motor associated therewith has been operated to the other of said limits, said switches being so connected that actuation thereof stops the associated motor, and manually controllable relay means for running all of said motors independently until each motor actuates one of said limit switches, whereby the settings of said motors are re-synchronized at said one of said limits.

17. In an electric system, a plurality of electric motors, switching mechanism including a member manually movable in either direction, relay means actuated by movement of said member in one direction to cause said motors to start, run in one direction a selected amount between limits and stop in synchronism and actuated by movement of said member in the other direction to cause said motors to start, run in the opposite direction a selected amount between said limits and stop in synchronism to thereby change the settings of the several motors by equal amounts in either direction, a separate double throw switch for each motor, relay means actuated by closure of each switch in one position to run the respective motor independently in one direction and actuated by closure of each switch in the opposite position to run the respective motor independently in the opposite direction to change its setting with respect to that of the other motors, a pair of limit switches associated with each motor, one switch of each pair being arranged to be actuated when the motor associated therewith has been operated to one of said limits and the other switch of said pair being arranged to be actuated when the motor associated therewith has been operated to the other of said limits, said switches being so connected that actuation thereof renders the first-mentioned relay means inoperative to run said motors in synchronism, and manually controllable means for running all of said motors independently until the respective motors are at one of said limits to thereby re-synchronize the settings of said motors.

ERIC C. WAHLBERG.
